F. ROSA

ELECTROSCOPE AND CHARGING DEVICE THEREFOR

Filed Dec. 28, 1923

Inventor
F. Rosa
By Marks & Clark
Atty.

UNITED STATES PATENT OFFICE.

FERDINANDO ROSA, OF MILAN, ITALY.

ELECTROSCOPE AND CHARGING DEVICE THEREFOR.

Application filed December 28, 1923, Serial No. 683,244, and in Italy March 10, 1923.

The present invention relates to a small sized easily portable electroscope of the so-called gold leaf type, in which the leaf of gold or of some other metal, for instance 5 aluminium, capable of replacing it, is diverged when an electric charge is imparted to it.

The invention essentially consists in the fact that in the electroscope a device is embodied adapted to impart to it an electric charge most quickly and through a simple manoeuvre performed by hand without risk of rupturing and spoiling the leaf of gold or of any other material susceptible of being 10 affected by the charge, the said device consisting in a brush carried by a pivotal member which can be suitably swung in such a way that the brush rubs against a metal ball lagged with insulating material 15 and arranged opposite one face of the gold leaf when the latter is in its rest position.

The spirit of the invention will be readily understood on reference to the accompanying drawing, which is a cross section 20 through the apparatus forming the subject matter of the invention in one of its execution forms that has been chosen by way of example.

As may be seen from the drawing, the improved electroscope at issue comprises a vertical bar —1—, to one face of which is secured at —2— the metal leaf —3—; to the opposite face of the said bar is fixed a metal ball —5— coated with suitable insulating material, for instance gum lac. On a pivot —7—, supported in the end walls of the apparatus box or casing —15—, swings a double-arm lever —6—10—, to the hub of which the brush —8— is secured. 25 By suitably operating the lever arm —6—, which extends to the outside across a slot —17— cut in the casing —15—, the brush —8— can be rubbed against the ball —5—. It is just this rubbing that imparts the electric charge to the apparatus; a few strokes 30 of the arm —6— suffice to electrify the ball —5— as well as the leaf —3—. The leaf then moves from the position indicated in full lines to the position indicated by dotted lines in the drawing.

Of course by varying the number of

strokes of the arm —6— the electric charge can be adjusted so as to obtain a greater or smaller deviation of the leaf —3—.

To the other arm —10— of the double-arm lever is attached one end of the return spring —9—, the other end of which is fixed at —11—, the purpose of this spring being to bring the arm —10— back to its rest position as soon as the arm —6— is released. 55 Opposite the leaf —3— is arranged in the ordinary way the plate —12— serving to press the leaf —3— against the bar —1— and thus protect it when the apparatus is not in use; this plate can be moved backwards and forwards, being yet maintained parallel to the bar —1—, by operating the knob —18— of the rod —19— by which the plate —12— is carried. The plate —12— side facing the leaf —3— is coated with a 60 layer of insulating paint —16—, so that when the leaf —3— is charged while the plate —12— is away from it, the leaf —3—, if it is made to reach the plate —12— as can be obtained by imparting to the electroscope a charge of sufficient intensity, 65 remains adherent to the said plate and in nearly horizontal position and maintains this position until the electroscope is discharged.

The apparatus is completed by a stem 70 —20— ending at the top in a knob —14— and capable of being revolved in a sleeve —21—. From the bottom end of the stem —20— is suspended the bar —1— so that the latter can be turned when, for instance, 75 it is desired to inspect the leaf —3—.

The electroscope just described, being readily portable and permitting of being easily and quickly charged lends itself quite well to the industrial investigation of the 80 electric conductivity of certain bodies and substances, the said conductivity affording a basis on which in many cases a judgment can be formed as to the quality of the body or substance at issue, for instance in the textile trade, in the industry of insulating materials etc.

Of course the constructional and form details may be varied in actual practice from those shown and described within the spirit 85 and scope of the invention.

Having now particularly described and

ascertained the nature of my said invention and in what form the same can be performed, I declare that what I claim is:

5 In combination with a portable electro-
scope of the leaf type, a device adapted to
quickly impart an electric charge to the
electroscope, said device including a metallic ball arranged laterally of the electroscope

leaf when the latter is in rest position, a
coating of insulating material on the ball, a
brush, and a member carrying the brush and
mounted for oscillating movement whereby
the brush may be caused to rub against the
ball.

In testimony whereof I affix my signature
ROSA FERDINANDO.
